G. RAMSEY,
SIDE SEAL CLOSURE,
APPLICATION FILED MAY 15, 1917.

1,327,963.

Patented Jan. 13, 1920.

INVENTOR
George Ramsey

UNITED STATES PATENT OFFICE.

GEORGE RAMSEY, OF BROOKLYN, NEW YORK, ASSIGNOR TO ANCHOR CAP & CLOSURE CORPORATION, OF BROOKLYN, NEW YORK, A CORPORATION OF NEW YORK.

SIDE-SEAL CLOSURE.

1,327,963.

Specification of Letters Patent. Patented Jan. 13, 1920.

Application filed May 15, 1917. Serial No. 168,801.

To all whom it may concern:

Be it known that I, GEORGE RAMSEY, a citizen of the United States, and a resident of the city of Brooklyn, in the county of 5 Kings, State of New York, have invented certain new and useful Improvements in Side-Seal Closures, of which the following is a specification.

This invention relates broadly to sealing 10 closures, and more particularly to sealing closures adapted for use with glass jars and similar containing receptacles.

The principal object of the present invention is to provide a closure and package of 15 the character specified wherein the closure is adapted to be secured in position on the receptacle by merely forcing the sealing cap over the side walls of the receptacle and the sealing cap is retained in position by 20 frictional engagement of portions of the cap with the side wall of the container.

A further and primary object of the present invention is to provide a sealing cap and a sealed package of the character specified 25 wherein the seal effected is a hermetic seal secured and maintained by a cap of the friction type.

A further and equally primary object of the present invention is to provide a friction cap adaptable to be sealed on substantially a straight walled container and wherein 30 in the contact between the side wall of the container and the skirt of the cap comprises primarily a plurality of separated friction surfaces.

A still further and important object of the present invention is the production of a friction seal cap adaptable for use in a vacuum sealing machine whereby a package 40 may be sealed under a vacuum which is effectively maintained by the operation of the cap when positioned over a suitable closure.

Another object of the present invention 45 is to provide a closure cap wherein the skirt of the cap is designed to expand circumferentially to provide friction engaging surfaces that are maintained under pressure against the side walls of the container to 50 secure and retain the cap in position upon a suitable package.

Other and further objects of the present invention will in part be obvious and will in part be pointed out hereinafter in the specification following by reference to the accom-

panying drawings forming a part of this application, and wherein like characters are used to designate like parts throughout the several figures of the drawings.

Figure 1 is a detail view showing a cap 60 comprising one form of this invention in position on a suitable container.

Fig. 2 is a section taken on line A—A Fig. 1.

Fig. 3 is an enlarged view of a section of 65 the skirt of a cap prior to its being expanded by being placed on a suitable container.

Fig. 4 is an enlarged detail view showing 70 the expansion of the skirt of a cap when in position on a container.

Fig. 5 is a sectional view taken on line B—B Fig. 3.

Fig. 6 is a detail view taken on line C—C Fig. 4.

Fig. 7 is a detail view taken on line D—D 75 Fig. 4.

Fig. 8 is a view illustrating the complete package comprising a jar with a cap in position thereon.

Fig. 9 is a detail view illustrating one 80 form of a cap comprising this invention with the gasket material arranged adjacent the cover portion of the cap to comprise a top and side seal.

It is the intention of the present invention 85 to provide a corrugated skirt on a metal cap whereby the corrugations may be expanded or distended when the cap is forced over a substantially incompressible side wall of a container, for example, a glass jar, and 90 wherein the tendency of the metal to contract produces a tight friction seal between the skirt of the cap and the side wall of the container. This construction permits one size of cap to be used on glass wherein the 95 variation from a fixed dimension is relatively large so far as this type of closure is concerned. Under certain conditions it may be desirable to provide a hermetic seal with a cap of this character and the construction 100 of the present cap is such that it may be conveniently filled with a suitable sealing material, such as chicle gum or other suitable semi-plastic material which may comprise a gasket or packing between the cap 105 and the container to hermetically seal the joint therebetween.

For many purposes it is not essential that the joint be sealed so that the present cap may be used without the packing or gasket material. The inven- 110

tion may take on several specific constructions, but preferably the corrugations are formed of curved grooves with the concave side of the groove on the outside of the skirt with the bead adapted to contact with the outside side wall of the container. Also where the sealing material is used it may be disposed in various portions of the cap to form either a side or top seal, as will be hereinafter more fully explained.

Referring now to the drawings, the cap comprises a cover portion 1 to which is attached a dependent skirt 2. The depending skirt may be variously formed in such manner as to be capable of circumferential expansion, but preferably is provided with an annular inwardly curved bead traversed by a plurality of corrugations 4, which thereby in cross-section somewhat resembles a distended spring. If desired these corrugations also may be formed upon an arc, as indicated as at 5, Fig. 5. The uncorrugated portions of the cap material above and below the inwardly curved annular bead form comparatively non-expansile restricting members, which act under tension to hold the corrugated portion stressed under compression against the side of the vessel when the cap is in use. The inwardly curved annular bead gives the skirt a desirable transverse flexibility within the limitation imposed by the uncorrugated restricting portions, and the corrugations permit the necessary circumferential expansion of the annular bead to accommodate the expected variations in contour of the vessel. The lower margin of the skirt is left unbeaded to permit a desirable flexibility whereby the skirt may be accommodated to the contour of vessels which are out of round, while still exercising the restricting function upon the expansile beaded portion of the skirt. Such caps may be used in a vacuum sealing machine, and as previously specified may form a hermetic seal with a suitable container by providing a semi-plastic gasket material which may fill the corrugations and portions of the cap, as at 6. Where the gasket material is disposed as indicated in Figs. 5, 6 and 7, the construction forms substantially a side seal. Where the gasket material is disposed, as at 7, in Fig. 9, the seal is substantially a top seal, although, a certain portion the gasket material forms a side seal, as at 8. In this type where the package is sealed under a gasket the atmospheric pressure on the cover portion 1 maintains the gasket material under both downward and inward pressure, as at 7 and 8 respectively. In sealing this type of package no particular or special type of machinery is necessary other than devices capable of causing relative movement of the container 9, which may comprise a glass jar or other suitable article, and the skirt of the closure

cap. As above stated where the package is sealed under vacuum the well known type of vacuum machine capable of producing such relative movement may be used for sealing purposes.

Realizing that the present invention may be embodied in structures other than the specific disclosure herewith it is desired that the specific construction illustrated and described should be understood as illustrative and not in the limiting sense.

Having thus described my invention what I claim is:

1. A closure for glass receptacles and the like comprising a top portion, a skirt depending from said top portion, a groove on the exterior of said skirt to form a bead on the interior of said skirt, and transverse corrugations extending across said groove and terminating short of the margin of the skirt and providing friction members on the interior of said skirt adapted to contact with and engage the side wall of a suitable receptacle to frictionally maintain said cap in position upon such receptacle.

2. A closure cap for glass walled receptacles and the like and comprising, a cover portion, a skirt depending from said cover portion, said skirt being constructed to form a bead on the interior thereof, a plurality of corrugations formed entirely in said bead and extending transversely thereof, and gasket material carried by said cap and being adapted to form a hermetic seal when said cap is forced over a suitable receptacle.

3. As an article of manufacture, a sealed package comprising a receptacle having a substantially incompressible straight side wall, in combination with a cap in position on said receptacle and sealing the same, said cap comprising a cover portion, a skirt depending from said cover portion, said skirt being provided with corrugations having arcuate crowns extending transversely of said skirt, and means holding said corrugations under stress to maintain the innermost portions of said corrugations in frictional engagement with the said side wall of said receptacle.

4. A closure of the sort described comprising a cap of flexible sheet material having a depending annular skirt portion, said skirt portion being formed with an annular inwardly pressed resilient bead, and the portion of the material in said bead being formed with transverse corrugations for the purpose described.

5. As an article of manufacture, a closure comprising a cap of flexible sheet material formed with a cover portion, a depending skirt portion, the said skirt portion being provided with an annular bead of smaller circumference than the cover portion formed of a portion of the skirt material struck inwardly, and the said annular bead having

transverse corrugations formed therein and projecting inwardly from the bead.

6. A package including a container having a substantially incompressible arcuate 5 side wall, a cap of flexible material having a top portion extending across the mouth of the container, and a skirt portion encompassing the side wall, said skirt portion being provided with an annular bead formed 10 of a part of the material of the skirt pressed inwardly, a portion of the cap adjacent the junction of the top and skirt forming an annular channel, gasket material disposed in said channel and compressed between the 15 arcuate side wall of the container and the skirt of the cap to provide a side seal, and the annular bead portion of the skirt being provided with transverse corrugations, the crowns of which have frictional engagement 20 with the side walls of the container.
7. A closure comprising a cap of flexible sheet material having a top portion and an annular depending skirt portion, the skirt portion being formed with an annular inwardly struck bead comprising a portion of 25

the material of the skirt, the portions of the skirt material not included in the bead forming continuous circumferential restricting members, and the bead portion being formed with transverse corrugations for the purpose described. 30

8. A closure comprising a cap of flexible sheet material having a top portion and an annular depending skirt portion, said skirt portion being formed with an inwardly 35 pressed annular bead whereby the said skirt is rendered extensible in depth and the material of the annular bead being formed with transverse corrugations whereby said bead portion is rendered expansible circumferentially. 40

9. A closure of the class described comprising a cap including a cover portion and a depending resilient annular skirt portion, said skirt portion being formed with an inwardly pressed resilient bead extending in the circumferential direction of the skirt and with corrugations extending across the bead in the transverse direction of the skirt. 45

GEORGE RAMSEY.
